UNITED STATES PATENT OFFICE.

FREDERICK L. G. STRAUBEL, OF GREEN BAY, WISCONSIN.

FILE-CABINET.

No. 812,962.

Specification of Letters Patent.

Patented Feb. 20, 1906.

Application filed April 7, 1905. Serial No. 254,390.

To all whom it may concern.

Be it known that I, FREDERICK L. G. STRAUBEL, a citizen of the United States, residing at Green Bay, in the county of Brown 5 and State of Wisconsin, have invented a new and useful Improvement in File-Cabinets, of which the following is a specification.

My invention relates to an improvement in a cabinet with a receptacle in which sheet-music, as well as letters and commercial papers, can be filed vertically.

The object of my invention is to provide means for conveniently filing such sheets or papers and for ready reference to same after 15 having been filed. I attain this object by the mechanism and construction of a cabinet with a vertical filing-receptacle illustrated in the accompanying drawings.

Figure 1 is a sectional view of the cabinet, 20 exposing the interior of one side. Fig. 2 is a sectional view showing a different style of receding cover. Fig. 3 is a perspective view with parts cut away to show the interior of the filing-receptacle. Fig. 4 is a sectional 25 front view showing a portion of the cabinet on line A A in Fig. 1, where one side of the cover is pivotally attached to the inner side of the cabinet.

Similar figures refer to similar parts 30 throughout the several views.

The front 1 of the filing-receptacle is hinged at its lower part, and at its central or upper part at 2 it has pivotally attached thereto, one on each side, the front ends of 35 the connecting-rods 3 3. The receding cover, composed of side pieces 4, one on each side, and lid or cover 5, turns upon pivots which are similarly arranged on both the inner sides of the cabinet, one of said pivots being shown 40 at 6. At 7, a proper distance from and rearward of said pivots at 6, the rear ends of the connecting-rods 3 3 are pivotally attached to the side pieces 4. The length of said connecting-rods and the position of their ends 45 where they are attached to the side pieces 4 and hinged front 1 being properly calculated and adjusted completes the arrangement, which will, upon turning back the lid or cover 5, force out the hinged front to a suitable angle, as shown in Fig. 3 and by the dotted lines in Fig. 1, to permit of convenient access to the contents in the receptacle or for

the filing of same. Returning the lid or cover to close the top of the filing-receptacle the reverse of the motion produced in opening will draw back the hinged front to a vertical position.

8 is a sliding adjustable follower with its wing or main portion leaning backward at about the same angle as that of the hinged 60 front extending forward when the cabinet is open. Said follower should have a suitable base 9, provided with slides (shown at 10) that will permit of said follower being readily moved backward and forward. Said slides 65 should engage the receptacle-bottom, preferably within a longitudinal opening of said bottom to prevent the follower from tipping backward when the weight of the contents filed lean or bear against it. To hold said 70 follower at any desired point within the scope of the slides, it should be provided with a suitable clutch. In this case it is shown at 11 to be one of the ordinary kind, which grasps the rod 12 shown within the longitudinal opening of the receptacle-bottom and secured at 13 and 14.

I do not confine myself to the use of any particular kind of clutch or style of slides, as any of those of the ordinary kind in general 80 use for similar purposes may be considered suitable. Neither can I confine myself to any particular style of receptacle-cover, that being adaptable to various forms of construction, while the action it transmits by levers 85 and connecting-rods upon the hinged front might be the same.

In Fig. 2 the cover 5^a is shown to have below it the guide-roller 15 and attached to it at 17 the lever 16. The cover 5^a being forced 90 to recede within the rear portion of the cabinet, as shown by the dotted lines, carries with it the levers 16, which turning upon the pivots their opposite ends by means of the connecting-rods attached thereto force the 95 hinged front outward the same as in the construction previously described.

I am aware that prior to my invention filing drawers or receptacles with hinged fronts and sliding followers have been in use. I 100 therefore do not claim this, broadly; but

What I do claim as new, and desire to secure by Letters Patent, is—

In a cabinet, a filing-receptacle having a

sliding follower, a front hinged at its lower edge to the cabinet, members attached to the cover and pivotally connected to the ends of the cabinet, and links pivotally connecting 5 said members and the front, whereby the cover is adapted to swing inward to the rear portion of the cabinet and the front to simul-

taneously swing outward to an inclined position.

FREDERICK L. G. STRAUBEL.
